UNITED STATES PATENT OFFICE

SIDNEY M. WEISBERG, OF BROOKLYN, NEW YORK

DESIGN FOR A TIRE-INFLATION DEVICE

Application filed August 21, 1930. Serial No. 36,730. Term of patent 14 years.

To all whom it may concern:

Be it known that I, SIDNEY M. WEISBERG, a citizen of the United States, residing at 4621 16th Ave., Brooklyn, in the county of Kings and State of New York, have invented a new, original, and ornamental Design for Tire-Inflation Devices, of which the following is a specification, reference being had to the accompanying drawing, forming part thereof.

Figure 1 is a side elevational view of a tire inflation device showing my new design, and

Figure 2 is a top plan view of the same.

I claim:

The ornamental design for a tire inflation device, as shown.

SIDNEY M. WEISBERG.
